UNITED STATES PATENT OFFICE

LEONARD R. CARLEY, OF WATERTOWN, CONNECTICUT, ASSIGNOR TO THE PATENT
BUTTON COMPANY, OF WATERBURY, CONNECTICUT, A CORPORATION OF CONNECT-
ICUT

DESIGN FOR A BUTTON

Application filed November 22, 1932. Serial No. 46,110. Term of patent 14 years.

To all whom it may concern:

Be it known that I, LEONARD R. CARLEY, a citizen of the United States, residing at Watertown, in the county of Litchfield, and State of Connecticut, have invented a new, original, and ornamental Design for Buttons, of which the following is a specification, reference being had to the accompanying drawing forming part thereof, in which:

Fig. 1 is a top plan view of a button showing my new design;

Fig. 2 is a side elevation thereof; and
Fig. 3 is a bottom plan view thereof.

In the drawing, the line shading is used for accentuating the design and is not used for the purpose of designating colors.

I claim:

The ornamental design for a button, as shown and described.

LEONARD R. CARLEY.
